United States Patent Office

Des. 179,912

Patented Mar. 19, 1957

179,912

POT STRAINER OR SIMILAR ARTICLE

Laurence Stanley Marshall, Los Angeles, Calif.

Application June 27, 1955, Serial No. 36,707

Term of patent 3½ years

(Cl. D44—29)

Fig. 1 is a perspective view of the pot strainer or similar article showing my new design;

Fig. 2 is a rear elevation thereof;

Fig. 3 is a top plan view looking in the direction of the arrow 3 of Figure 2, and,

Fig. 4 is an end elevation looking in the direction of the arrow 4 of Figure 2.

I claim:

The ornamental design for a pot strainer or similar article, substantially as shown.
